UNITED STATES PATENT OFFICE

BENJAMIN H. HERBSTER, OF MILWAUKEE, WISCONSIN, ASSIGNOR, BY MESNE ASSIGNMENTS, TO BOSTON MACHINE WORKS COMPANY, OF LYNN, MASSACHUSETTS, A CORPORATION OF MASSACHUSETTS

APPARATUS FOR FORMING BACK HEEL SEAMS FOR FOOTWEAR

Original application filed September 24, 1927, Serial No. 221,734. Divided and this application filed April 5, 1930. Serial No. 441,834.

This invention relates to improvements in apparatus for forming back heel seams for footwear, and is a division of application Serial Number 221,734, filed September 24th, 5 1927, for Method for forming back heel seams for footwear, which matured into Patent No. 1,759,643.

Heretofore, shoe manufacturers have encountered difficulties in forming the back heel seam on shoes. The method formerly employed was to stitch the two quarters of leather together on the wrong side, apply a strip of adhesive tape thereto, and then turn the product right side out. This method was 10 15 fairly successful where a double row of stitching was used, but double stitching is objectionable because the seam formed thereby is not neat in appearance. When the aforementioned method was used with a single row of stitching, difficulties were encountered. After turning the product right side out, there was a pronounced bulging on one side of the seam, and the strip of tape on the inside would wrinkle. The result was 20 25 a cumbersome looking seam and a poorly shaped heel portion. For these reasons, it became very desirable to devise a new method for taping and smoothing out the seam.

It is one of the objects of the present invention to provide an apparatus for forming back heel seams for footwear which will produce a well shaped back heel portion of the shoe, and a seam crease which is neat in 30 35 appearance.

It is a further object of this invention to provide an apparatus for forming back heel seams for footwear in which a single row of stitching is employed.

It is a further object of this invention to 40 45 provide an apparatus for applying the strip of adhesive tape to the seam ridge and for smoothing out the seam ridge and shaping the heel portion when the quarters of leather are right side out or in their natural position.

A further object of this invention is to provide an apparatus for forming back heel seams for shoes which is simple, effective, and well adapted for the purpose described.

With the above and other objects in view,

the invention consists of the improved apparatus for forming back heel seams for shoes and all its parts and combinations as set forth in the claims, and all equivalents thereof.

55

In the accompanying drawings in which the same reference characters indicate the same parts in all of the views:

Fig. 1 is a side elevation of the improved apparatus for performing the combined operations of back seam pressing and tape applying, showing the device in attachment with a portion of a table;

Fig. 2 is an end view thereof;

Fig. 3 is a view of the opposite side of the machine from that shown in Fig. 1, parts being broken away and parts being shown in section;

Fig. 4 is a sectional view taken on line 4—4 of Fig. 3;

Fig. 5 is a sectional view taken on line 5—5 of Fig. 3;

Fig. 6 is a detail view of the front end of the machine, showing shoe quarters in position on the machine, parts being broken away;

Fig. 7 is a side view of a portion of the machine, showing the shoe quarters in position, parts being broken away and parts being shown in section;

Fig. 8 is a view of the inside of the finished product showing the attached strip of adhesive tape; and

Fig. 9 is an outside view of the finished product.

Referring to the drawings, the numeral 12 designates a base member which is arranged to be secured to a table 13. The base member is formed with a right angular arm 14 and a tubular extension 15. Within the tubular extension a bifurcated bearing 16 is slidably positioned. An adjusting screw 19 holds the bearing at any desired length within the tubular extension. Loosely mounted on a pin 18 and within the bifurcated end portion of the bearing is a back heel seam supporting member preferably in the form of a wheel or roll 19. Secured to the tubular extension 15 and having its upper end adjacent the wheel 19 is a tape guide 20 having an eye 21. The 100

upper portion of the arm 14 forms a bearing for the shaft 22. On the outer end of this shaft is a rigidly mounted outer pulley 23 and a rigidly mounted inner pulley 24. On 5 an intermediate portion of the shaft 22 is a tightly fitting eccentric sleeve 25. Loosely mounted on the eccentric sleeve is an outer collar 26 formed with a downwardly extending arm 27 having a vertically extending slot 28. A bolt 29 projects through this slot and into a bracket 30 which is secured to the arm 14. A spring member 31 held between pins 32 holds the arm 27 yieldingly in a raised position. Secured to and projecting 10 from the lower portion of the arm 27 is a seam smoothing member 33 having an engaging head 34. The front end of the shaft 22 is formed with an eccentric portion 35 which is smaller in diameter than the main part of 15 the shaft and which is positioned off the center of the shaft 22. Journaled on this eccentric portion is a feeding arm 36 having a vertical slot 37. A bolt 38 extends through this slot and into the arm 14. On the lower 20 end of the feeding arm 36 and adjustably positioned within a bore is an inverted T-shaped feeding member 39 having a groove 40 in its lower surface. A set screw 41 is arranged to adjust the feeding member 39 25 within the bore. Extending downwardly from a bracket 42 on the arm 14 is a guide finger 43. A spring 44 surrounding the upper portion of the finger and positioned 30 between extensions 45 holds the finger yieldingly in position.

The outer pulley 23 is rotated by means of a belt 46 which is connected with driving mechanism 47. The inner pulley 24 is connected by an endless belt with a lower pulley 48. The lower pulley is rigidly mounted on one end of a shaft 49 which is journaled in bearings 50, the latter being secured to the lower side of the table 13. On the other end of the shaft 49 a cranked arm 51 is rigidly 45 mounted. A bearing 52 also secured to the underside of the table has journaled therein a shaft 53, upon one end of which a tape holding wheel 54 is mounted. The wheel 54 is arranged to hold a roll of adhesive tape 50 which is fed to the machine.

The operation of the device is as follows: When the power is turned on, the driving mechanism 47 is set in motion and this is transmitted by the belt 46 and the pulley 23 55 to the shaft 22. As the shaft revolves, a reciprocal motion is imparted to the eccentrically mounted arm 27 and the leather smoothing member 33. A similar motion is given to the arm 36 by the eccentric 35. When the shaft 22 is rotating, motion is also transmitted by the pulleys 24 and 48 to the shaft 49. This causes the cranked arm 51 to rotate and pull the adhesive tape off of the roll, as illustrated in Fig. 2.

60 To form the back heel seam, the following

method is used: Two pieces of leather forming the quarters of a shoe are stitched together on the wrong side. They are then turned right side out, presenting a seam crease on the convex face of the work and a 70 seam ridge on the concave face of the work and placed in the machine on the wheel 19, as shown in Figs. 6 and 7. The guide finger 43 rests in the seam crease. Adhesive tape which passes from the roll over the cranked arm 51 and through the eye 21 in the tape guide 20, is in place on the wheel 19 with its 75 adhering side up. As the leather is fed in, the feed member 39 goes through the various positions shown by the dotted lines in Fig. 6, 80 pressing down upon and smoothing out the seam ridge and causing the adhesive tape to become affixed to the under side of the seam ridge. The feeding member 39 also tends to push or feed the leather further along the 85 wheel 19. The groove 40 in the feeding member is for the purpose of receiving the seam crease, as illustrated in Fig. 7. After the strips of leather have passed the feeding member, they are engaged by the head 34 of 90 the smoothing member 33. This member presses upon and smooths out the seam, shapes the heel portion of the shoe, and causes the marginal edges of the tape to be secured to the adjacent face of the work on 95 opposite sides of the pressed seam ridge. The finished products 56 are discharged from the machine, as shown in Fig. 6, and it is then necessary to cut off the projecting strips of 100 tape. By this method, a neat seam and a well shaped back heel portion of the shoe are produced, as illustrated in Fig. 9. The smoothing out of the seam and taping are both done while the leather is right side out, so the necessity of turning the leather over, 105 and the consequent bulging, is eliminated. The strip of adhesive tape is also affixed to the inner portion in such a manner that there are no wrinkles, as is illustrated in Fig. 8. That is, the marginal edges of the adhesive 110 tape are united to the concave face of the work on opposite sides of the seam ridge.

From the foregoing description, it may be seen that the improved apparatus for producing back heel seams for shoes is simple, 115 effective, and well adapted for the purpose described.

What I claim as my invention is:

1. A shoe machine comprising a back heel seam supporting member, and means engaging the outside of the seam for simultaneously smoothing out said seam and applying a strip of material from below over the inside thereof.

2. A shoe machine comprising a back heel seam supporting member, means for holding a roll of adhesive tape, means for removing said tape from the roll and for guiding the tape to the seam supporting member with the adhesive side of the tape up, and means 120

engaging the outside of the seam for applying the tape and causing the adherence thereof to the inside of the seam.

3. A shoe machine comprising a back heel 5 seam supporting member, means for holding a roll of adhesive tape, means for removing said tape from the roll and for guiding the tape with the adhesive side up to the seam supporting member, and a common means engaging the outside of the seam for smoothing out the seam and for applying to and causing the adherence of the tape to the inside of the seam.

4. A shoe machine comprising a back heel 15 seam supporting member, a wheel for holding a roll of adhesive tape, a cranked arm for engaging the tape and causing the removal thereof from the roll, a tape guide adjacent the seam supporting member, and a common 20 means engaging the outside of the seam for smoothing out the seam and for applying to and causing the adherence of the tape to the inside of the seam.

5. A shoe machine comprising a back heel 25 seam supporting wheel, a rotatable shaft, an eccentrically mounted feeding member having a grooved lower surface on said shaft, and an eccentrically mounted smoothing member also on said shaft.

30 6. A shoe machine comprising a back heel seam supporting wheel, a rotatable shaft, an eccentrically mounted feeding member and an eccentrically mounted smoothing member on said shaft, and a guide finger for engaging the crease of said seam.

7. A shoe machine comprising a back heel 40 seam supporting wheel, a rotatable shaft, an eccentrically mounted feeding member and an eccentrically mounted smoothing member on said shaft, and a yieldingly mounted guide finger for engaging the crease of said seam.

8. A shoe machine comprising a back heel 45 seam supporting wheel, a wheel for holding a roll of adhesive tape, a cranked arm for engaging the tape and causing the removal thereof from the roll, a tape guide having an eye adjacent the seam supporting member, a rotatable shaft, an eccentrically mounted feeding member and an eccentrically mounted smoothing member on said shaft, a yieldingly mounted guide finger, and means for revolving the rotatable shaft and the cranked arm.

55 9. Apparatus for applying tape to the ridged back seam of shoe quarters, comprising a presser head, a mandrel disposed beneath said head, and means for guiding the tape upon the mandrel in position to have the 60 ridge of said seam pressed against the tape by said presser head.

10. Apparatus for applying tape to the back seam of shoe quarters, comprising a presser head, a mandrel, and a guide member for guiding the tape upon the mandrel,

said guide having walls for shielding the work from contact with the tape at points in advance of the presser head.

11. In a seam pressing machine, the combination with means for supporting work having a concavo-convex formation comprising the pieces to form the heel portion of a shoe upper seamed together by a seam presenting a seam ridge on the concave face of the work and a seam crease on the convex face of the work, said means comprising a work support engaged with the concave face of the work, of means engaging the convex face of the work for subjecting the seam ridge to pressure. 70

12. In a seam pressing machine, the combination with means for supporting adhesive tape and also work having a concavo-convex formation comprising the pieces to form the heel portion of a shoe upper seamed together 75 by a seam presenting a seam ridge on the concave face of the work and a seam crease on the convex face of the work, said means comprising a work support engaged with the concave face of the work, of means engaging the convex face of the work for subjecting the seam ridge to pressure in contact with the tape on the work support. 80

13. In a seam pressing machine, the combination with means for supporting work having a concavo-convex formation comprising the pieces to form the heel portion of a shoe upper seamed together by a seam presenting a seam ridge on the concave face of the work and a seam crease on the convex face of the work, said means comprising a work support engaged with the concave face of the work, of means engaging the convex face of the work for securing adhesive tape to the seam ridge. 90 100

14. In a seam pressing machine, the combination with means for supporting adhesive tape and also work having a concavo-convex formation comprising the pieces to form the heel portion of a shoe upper seamed together 110 by a seam presenting a seam ridge on the concave face of the work and a seam crease on the convex face of the work, said means comprising a work support engaged with the concave face of the work, of means engaging the convex face of the work to press the seam ridge progressively, simultaneously secure adhesively coated tape to the seam ridge and cause the tape to be adhesively secured to the concave face of the work on opposite sides 115 of the seam ridge. 120

In testimony whereof I affix my signature.
BENJAMIN H. HERBSTER.
